INFLATABLE TOY OR THE LIKE

Martin John Gilman, Gilman, Conn.

Application December 8, 1947, Serial No. 143,041

Term of patent 14 years

(Cl. D34—5)

To all whom it may concern:

Be it known that I, Martin John Gilman, a citizen of the United States, residing at Gilman, in the county of New London and State of Connecticut, have invented a new, original, and ornamental Design for Inflatable Toy or the like, of which the following is a specification, reference being had to the accompanying drawing, forming a part hereof.

I claim:

The ornamental design for an inflatable toy or the like, as shown.

MARTIN JOHN GILMAN.
